(57) **CLAIM**

The ornamental design for a charging apparatus for delivery robot, as shown and described.

DESCRIPTION

FIG. 1 is a top, front and right side perspective view of a charging apparatus for delivery robot showing our new design;

FIG. 2 is a front view thereof;

FIG. 3 is a rear view thereof;

FIG. 4 is a top view thereof;

FIG. 5 is a bottom view thereof;

FIG. 6 is a right view thereof; and,

FIG. 7 is a left side view thereof.

The broken lines in the figures depict portions of the article which form no part of the claimed design.

1 Claim, 7 Drawing Sheets

FIG. 1

FIG. 2

FIG. 3

FIG. 4

FIG. 5

FIG. 6

FIG. 7
